UNITED STATES PATENT OFFICE.

JAMES M. CORNETT, OF KEWANEE, ILLINOIS.

GRAIN-SHOCKER.

1,165,650.

Specification of Letters Patent. Patented Dec. 28, 1915.

Application filed July 24, 1912. Serial No. 711,355.

To all whom it may concern:

Be it known that I, JAMES M. CORNETT, a citizen of the United States, residing at Kewanee, in the county of Henry and State of Illinois, have invented certain new and useful Improvements in Grain-Shockers, of which the following is a specification.

This invention relates to improvements in what may be termed grain shockers, especially adapted for use in connection with grain binders.

The invention has for its object to provide for suitably receiving the grain-bundles or shocks from the binder, and suitably delivering or dropping the bundles or shocks securely or effectively tied and in a standing or vertical position to the ground.

In the accompanying drawings, illustrating the preferred embodiment of my invention wherein it will be understood that various changes and modifications may be made as relates to the detailed construction and arrangement of the parts without departing from the spirit thereof:—Figure 1 is a plan view of my invention; Fig. 2 is a side elevation thereof; Fig. 3 is a rear elevation of the same; Fig. 4 is a fragmentary bottom plan view of the under part of the shocker, showing more particularly the primary 15 crank-shafts, with their coöperative lugs, through which the jointed members of the shocker-dropping mechanism are actuated; Fig. 5 is an enlarged detailed view of the members 29 and 31 of the feeding and packing contrivance; Fig. 6 is an enlarged fragmentary detailed view, showing more especially the intermittently intergearing mechanism for actuating the binding cord-carrying needle; Fig. 7 is a detail view in elevation of a portion of the mechanism; Fig. 8 is a detail perspective view of a portion of the mechanism; Fig. 9 is a still further detailed view disclosing more particularly the bearing-forming pocket of one 45 end of the shaft carrying the shiftable pinion for bringing into action the needle, the knotter and the bundle-dropping platform.

In carrying out my invention, I mount a suitable carrying frame 1, at its rear end, upon an axle 2 equipped with wheels 3, the forward end of said frame being borne, when disconnected from the grain binder by 50 castor wheels 4 whose axles are carried by rod-like forked members 5 suitably swiveled in position at said end of the frame, this

arrangement being provided for the suitable transportation or support of the device or machine in moving or hauling the same from place to place, disconnected from the grain-binder. Said frame is suitably connected to the grain-binder by means of a pivoted tongue-like member 6, itself suitably connected to a forward-end cross bar of said frame and which member 6 is suitably supported out of the way when the shocker is disconnected from the grain-binder, by being swung laterally in between parallel bars 7 outstanding from said end of the frame 1, said tongue-member being thus 70 clasped in such position.

Suitably hinged or pivoted, at their outer longitudinal edges, to longitudinal bars of the frame 1, a suitable distance from the ground, are horizontal edgewise-opposed platforms or bottoms 8, the hinging or pivoting points therefor being designated as 9, said platforms or bottoms having fixed thereto and projecting therefrom arms 10, to which are pivoted articulated or knuckle-jointed sectional braces or rods 11 pivotally connected to the outer sides of additional longitudinal bars of the frame 1. Said knuckle-jointed sectional braces 11 are normally held against an outwardly flexing action, as occurs when the platforms or bottoms are tilted or depressed, by the action of springs 12 connected to said braces and the frame 1, which tilting or depressing action of said platforms or bottoms and 90 the means for accomplishing the same will be later described.

At the forward, or grain-binder-attached end of the frame 1 is arranged an endless inclined conveyer or apron 13 encompassing or engaging a small-diametered roll 14, hung upon and near the upper ends of uprights of said frame; said apron also engaging a second small-diametered roll 15 whose shaft is hung upon lower longitudinal members 100 of said frame a short distance inwardly from the forward ends thereof, the actuating means for said apron 13 being later described. Said apron receives and conveys the cut grain from the binder, and suitably arranged at the lower end or base of said apron are two additional endless conveyers 16, to take the grain from the aforesaid apron or conveyer and deliver it still farther into the shocker, to the action of certain other devices, as presently described, adapted to dispose and retain the grain suit-

ably in vertical position or perpendicular. The conveyers 16, the axes of whose encompassed rolls 17 are at right angles or perpendicular to the axes of the rolls encompassed 5 by the apron 13, are caused to engage the grain laterally, the shafts 18 of said rolls 17 being journaled in upper and lower bearing-members 19 secured to transverse members or bars 20 fixed to the carrying frame 10 1. The rolls 17, engaged by the conveyers 16, are also of different diameters, those of smaller diameter being arranged inwardly from the larger forward ones in order to deflect or incline those portions or lengths of 15 the conveyers, facing or engaging the grain-bundles laterally increasing distances apart, to allow of the spreading to that extent of the grain, to fully utilize the containing capacity of the shocker.

20 Suitably arranged, intermediate the conveyers 16, opposite the forward rolls thereof, is a guard or arm 21 to aid in holding the incoming grain in perpendicular position as it passes to, and between, said conveyers, said arm serving to prevent the top ends of the bundles of grain from falling over upon the conveyers 16 as the butt-ends thereof are being directed downwardly upon the apron 13. Said guard or arm is sectional, one member or section being suitably held in position upon the frame 1, the other member or section being pivoted, as at 22 to the aforesaid member or section and resiliently or flexibly held in alinement 30 therewith by means of a preferably flat-metal spring 23 suitably secured to one arm section, and so applied with respect to the other arm section as to allow it to yield or flex under the pressure of the grain-bundles 35 as the latter are forced against it, and yet resume its initial or effective position after the release of the grain-bundle therefrom.

An edgewise-disposed member 24, which may be termed as a divider, is preferably in 45 board-like outline and arranged and fixed about centrally and longitudinally of the frame 1 or shocker, and adapted to thus sub-divide the frame into two grain-receiving compartments, said divider or partition 50 extending nearly the entire length of the shocker, from a point contiguous to the conveyers 16 to the rear end thereof, as shown.

A turnstile-like arrangement of connected arms 25, preferably three in number, and 55 suitably tapered toward their free ends, is mounted and pivoted upon the upper end of a vertical shaft or post 26 secured about in alinement with, and close to the forward end of the partition or divider 24, for alternately delivering the grain-bundles into the compartments at opposite sides of said partition or divider, the two inner arms being alternately engaged and limited in their 60 movements by the latter as they are reciprocated or swung horizontally by the con-

tact of the grain-bundles with the third or forward arm. To state this delivering action of the grain bundles with respect to, and into said compartments more fully, it will be seen that as a grain-bundle is delivered against the forward arm when in the position as shown in Fig. 1, said grain-bundle will be conducted into the right-hand compartment and that, as the grain-bundle passes from said forward arm upon the 70 alining inner or rear arm, it will swing said forward arm into a reversed position as indicated in dotted lines, and thus provide for the delivery of the successive grain-bundle into the left-hand compartment. The 75 grain-bundle, in passing from the forward arm in said reversed dotted-lined position against the alined inner arm, will accordingly throw or swing said forward arm to the first-referred-to position for a repetition of the aforesaid operation, this action being continued until said compartments have received the requisite quantity of grain-bundles for formation into the shock.

Suitable spring-metal or resilient fingers 80 27, themselves connected by coiled or helical continuations 28, in suitable manner, to the inner surfaces of upright or other members of the frame 1, normally occupy such position as indicated as to receive the grain-bundles between them and the partition or divider 24, said fingers, by reason of their resiliency automatically delivering pressure upon the grain-bundles and pressing them toward the partition, and uniting with said partition or divider to retain the grain-bundles in upright position, for delivering or dropping the same, as previously stated, securely tied, in perpendicular position upon the ground, as will be more fully seen later.

Opposed sliding or reciprocating members or rods 29^a and 29^b, are supported and guided upon the inner surfaces of members of the frame 1, within suitable eyes or keepers 30 secured to the latter, said rods 110 or members 29^a and 29^b being provided or equipped with resiliently-seated or yielding "kickers" or plungers 31 each rod having a number or plurality thereof for engaging and effectively feeding or packing the grain-bundles suitably into the shocker compartments aforesaid. The resilient or yielding action of the "kickers" or plungers allows of their readily escaping the grain-bundles in performing their return strokes or movements. The plunger or "kicker"-carrying rods 29^a and 29^b of each set are connected to a pitman at 29 and these pitmen, indicated in the drawings by the numeral 32, are connected, one to a crank 33, connected to a 115 shaft 34 suitably supported or journaled in longitudinal members of the frame 1 and the other pitman 32 to a beveled gear-wheel 35 also connected to the shaft 34, the wheel 35 meshing with and being driven by a cor-

responding beveled gear-wheel 36 carried by a vertical shaft 37 suitably journaled upon an upright member of the frame 1. The lower end of the shaft 37 is intergeared with a driving shaft 38^a receiving its motion from the rear axle 2, the pinions or wheels effecting intergeared connection between the shafts 37 and 38^a, being designated as 39 and 40 respectively (Fig. 2). Shafts 38 and 38^a are intergeared with said axle through the beveled pinions 42 and 42' respectively (Fig. 1) a suitable spring-actuated clutch 43 adapted to be operated by a manually actuated lever 44, being employed for coupling said shaft 38 to said axle for throwing the parts controlled thereby into and out of operations. The driving shaft 38^a is also equipped with a spring actuated clutch 74 suitably actuated by a manually or hand 20 operated lever 75.

A needle 45 is suitably supported in position in the frame 1 to have transverse or horizontal movement in a bracket 47, the needle being actuated by a toothed wheel 46 whose axle 46^a is suitably journaled in the frame, the teeth of said wheel engaging notches or apertures in said needle for effecting such movement of the needle. Said needle suitably receives and carries the bundling cord or twine 48, the bulk or ball of which is placed in a suitable holder or receptacle 48^b supported upon the frame 1 at one end, said cord or twine being shown as in the position it assumes when encompassing the bundles in forming the shock, and having one end suitably connected to the knotted 50 shown simply diagrammatically, the same in its structural features constituting no part of the invention only in a general way.

Suitable tension means 48^a is provided in connection with the passage or delivery of the cord or twine to the needle, and is shown simply diagrammatically, the same in its structural features constitutes no part of the invention only in a general way.

The means for actuating the needle-operating wheel 46, includes preferably a crank 51 having connected thereto a rod or pitman 52 eccentrically connected to said wheel, said crank being carried and actuated by a shaft 53 suitably hung upon the underside of frame 1 and driven by intergeared pinions 54 and 55. The pinions or gear-wheels 54 and 55 are secured upon the shaft 53 and a shaft 56 journaled upon one side of the frame 1, the pinion or wheel 55 being driven or receiving motion through a pinion 57 carried by a shaft 58, suitably journaled in a vertically movable bearing member 58^a. Said shaft 58 has a second pinion 59 thereon geared to a pinion 60, said pinion 60 being carried by driving shaft 38 suitably hung upon frame 1 and intergeared with the driving shaft 38^a through the beveled or

intergeared pinions 62 and 63, secured upon the shafts 38 and 61 respectively and gears 68 and 69, as seen in Fig. 4.

The vertically movable support or bearing 58^a for the shaft 58 is guided in its movements within a suitable keeper or bracket 58^b secured to the side of the frame 1, and to said support or bearing, is connected a rod or stem 60^a itself guided within a keeper or bracket 60^b likewise secured to said frame. The shaft-support or bearing 58^a is resiliently held in initial position by means of a spring 61^a interposed between the bracket or guide 60^b and the upper end of said shaft-support. The lower end of the shaft 56 carrying the beveled pinion 55, carries a preferably disk-shaped member or ledge 56^a said ledge or member having a depression or pocket 56^b therein for reception of, and forming a bearing for one end 85 of the shaft 58.

A bell-crank lever 62^a has one arm connected to the upper end of the shaft-support suspending rod 60^a and to the opposite arm of said bell-crank is connected one end 90 of a slideable or movable rod 63^a suitably supported and guided in keepers, or brackets 63^b secured to the frame 1. To the slideable or movable rod 63^a is connected one end of a chain 63^c or other flexible connection, 95 passed over a pulley 63^d suitably hung upon the frame 1, the opposite end of said connection or chain being connected to a notched eccentric 60^e acting in the capacity of a lever and suitably pivoted upon said frame.

Extending from the inner side of one of the shock-forming compartments is a lever 60^e arranged for actuation by the engagement therewith of the grain-bundles, for forming the shock, as said grain-bundles about fill said compartments. The lever 60^e is suitably pivoted in position upon the frame 1 and spring-actuated as at 61^d and has connected to one end thereof a pawl-like member 50^a engaging the notch of the eccentric or lever 60^e, all as will be observed from Fig. 8.

Driving mechanism for the conveyer 16 includes preferably a horizontal shaft 64 intergeared with two of the shafts 18 of said conveyers, the intergeared wheels or pinions being designated as 65 and 66 secured upon said shafts 64 and 18, respectively; and means for actuating the apron or conveyer 13 includes preferably an endless link belt 72 encompassing sprocket or toothed wheels 73 secured upon the shafts of the pulley 15 seen in dotted lines in Fig. 1. The gear 41 meshes with a gear 69^d upon the shaft 64.

The means for actuating the platforms or bottoms 8 includes shafts 76^a mounted upon the frame and having crank ends 76. Rods 76^b are connected at their upper ends to the

cranks 76 and at their lower ends to cranks 78 on a shaft 77. The shaft 76^a has fixed upon it cam arms 76^a coöperating with the sections of the jointed members in a manner to be presently explained. The shaft 77 is provided or equipped with a lug 79 adapted to be engaged by a like lug 80 carried by the shaft 53, the action of these lugs one upon the other being so controlled or 15 timed by their relative arrangements and the respective crank-connections and gearing hereinbefore described that previous to delivering the dropping action to the platforms or bottoms the tying or knotting action 20 will have been imparted to the cord 48, as it is thought, has been made plain.

It will therefore be observed from the foregoing it being presumed that the machine is in operation, that, when the grain-bundles have been fed into the respective shock-receiving compartments so as to effect, engagement with, and actuate the lever 60^a it is apparent that the action of the parts 25 50^a, 60^a, 63^a, 63^b will have the effect to move the rods 63^a rearwardly. These movements of parts will actuate the bell-crank levers 62^b which, in turn will move the shaft-support-suspending member 60^a upwardly and accordingly effect the engagement of the 30 pinion 57 with the pinion 55, the pinion 59 still maintaining engagement with the pinion 60. Also, it will be noted that simultaneously with this action of parts, the free end of the shaft 58 will be lifted out of the 35 pocket 56^b of the ledge or disk 56^a and be supported upon said ledge or disk and remain thereon until the shaft 56 has, by its rotation, returned said pocket to its initial position, to again receive that end of the 40 shaft 58. In the interim, however, said action of parts will, through the shafts 58 and 53 and intermediate gearing, actuate the pitman 52 and crank 51 which in turn will actuate the needle-operating wheel 46, 45 imparting the required movement to the needle which will effect the application of the cord 48 to the thus formed shock. Also, simultaneously with this action of parts, the shaft 56 will actuate the knotter 50 and thus 50 effect the tying of the binding cord 48, as is apparent, while the interacting lugs 79 and 80 on the shafts 53 and 77 will, as previously stated, provide for moving the cam-forming arms 76^a of the member 76^b into 55 contact with the jointed members 11, thus effecting the flexing of the latter and accordingly causing the tilting of the platforms or bottoms 8 and the depositing of the shock perpendicularly upon the ground, the 60 springs 12 then straightening the sections of the members 11 which will effect the elevation of the platforms or bottoms 8 to their initial or horizontal position. The spring 61^a will also at the same time, provide for the disengagement of the pinion 57

from the pinion 55, thus disconnecting the operation of the knotter and arresting the needle actuating mechanism, the needle by the reciprocatory movement imparted to the wheel 46 having been returned to its initial 70 position. Also, with the movements of parts, the bell-crank lever 62^b will be so actuated as to allow the rod 63^a to be moved forwardly as the action of the spring 61^b returns the lever 60^a to its original position. 75

It will be noted that the tension device 49, with the knotter 50 and its actuating shaft 56, also the tripping lever 60^a are all adjustably supported in position, in order to accommodate the same to bundling or 80 shocking tall and short grain, as will be readily understood.

I claim:—

1. A grain-shocker, including a hinged platform, a flexible retaining member for 85 said platform, resilient means for holding said retaining member against casual flexing action, a jointed member, having a cam-actuating arm adapted to engage and flex said retaining member, and means for actuating said jointed member and its cam-actuating arm for tilting said platform. 90

2. In a grain shocker, a platform supported for swinging movement, a jointed bracing member normally holding the platform in supporting position, and shock actuated means coacting with said jointed bracing member and operable to break the joint and thereby allow the platform to drop, the sections of the jointed bracing 100 member being normally in alinement.

3. In a grain shocker, a platform supported for swinging movement, a jointed bracing member normally holding the platform in supporting position, means yieldably holding the sections of the jointed bracing member in alinement and in position to support the platform, and means coacting with the said jointed bracing member operable to break the joint and thereby allow 110 the platform to drop.

4. In a grain shocker, a bundle receiving chamber having side walls, a platform supported for swinging movement at the bottom of one of the side walls and constituting the bottom of the chamber, a bracing member for the platform including pivotally connected links, the links of each bracing member being connected one to the platform and the other to the side wall of the 115 chamber and arranged when in alinement to hold the platform in supporting position, means yieldably holding the links in alinement, and means coöperating with one of the links and operable to break the joint and thereby allow the platform to drop.

5. In a grain shocker, a platform supported for swinging movement, a jointed bracing member normally holding the platform in supporting position, a shaft mount- 120

ed for rocking movement, means operable to rock the shaft at a predetermined period in the shocking operation, and a cam arm carried by the shaft and riding against one of 5 the sections of the jointed bracing member and arranged to break the joint and thereby allow the platform to drop to discharge a bundle supported thereon.

6. In a grain shocker, a lever arranged 10 in the path of movement of the grain bundles, tying mechanism including a gear, a shaft, a movable bearing for the shaft, a pinion carried by the shaft in juxtaposition to the gear, means for rotating the shaft and 15 connection between the said bearing and the lever whereby when the lever is engaged by a bundle and rocked, the shaft bearing will be moved to bring the pinion into mesh with the gear whereby to transmit motion 20 to the tying mechanism.

7. In a grain shocker, a bundle receiving 25 chamber, a needle movable transversely of the chamber and having a series of sockets, a toothed wheel having its teeth engaging said sockets, means for rotating said wheel including a gear, a shaft, a movable bearing for the shaft, a pinion carried by the shaft in juxtaposition to the gear, means for ro-

tating the shaft, a lever arranged in the path of movement of the grain bundles in the receiving chamber, and connection between the bearing and the lever whereby when the lever is engaged by a bundle and rocked, the shaft bearing will be moved to bring the pinion into mesh with the gear and 35 thereby impart motion to the means for rotating the said toothed wheel.

8. In a grain shocker, a lever arranged in the path of movement of the grain bundles, tying mechanism including a gear, a shaft, 40 a movable bearing for the shaft, a pinion carried by the shaft in juxtaposition to the gear, means for rotating the shaft, connection between the said bearing and the lever, whereby when the lever is engaged by a 45 bundle and rocked, the shaft bearing will be moved to bring the pinion into mesh with the gear, whereby to transmit motion to the tying mechanism, and means for supporting the shaft with the pinion in such position 50 during the period of operation of the tying mechanism.
